UNITED STATES PATENT OFFICE.

HENRIE D. STONE, OF BOSTON, MASSACHUSETTS, ASSIGNOR TO GEORGE A. WHITE, OF SAME PLACE.

MACHINE FOR MAKING BUNDLING-WIRE.

SPECIFICATION forming part of Letters Patent No. 508,256, dated November 7, 1893.

Application filed May 9, 1893. Serial No. 473,631. (No model.)

To all whom it may concern:

Be it known that I, HENRIE D. STONE, of Boston, county of Suffolk, State of Massachusetts, have invented an Improvement in Machines 5 for the Manufacture of Bundling-Wire, of which the following description, in connection with the accompanying drawings, is a specification, like letters and figures on the drawings representing like parts.

10 This invention has for its object the production of a machine for the manufacture of continuous bundling wire or a wire bent upon itself at desired intervals to form a series of loops or eyes, such wire being useful in securing bundles, the loops or eyes greatly aiding in applying the wire tightly to the articles to be packaged or held together, and also furnishing convenient means by which to secure the 15 ends of the bundling wire when passed about 20 such articles.

In accordance with this invention, I provide suitable devices for acting upon and looping the wire and twisting the loop to form an eye.

In the preferred form of machine, the wire 25 is grasped by a twisting hook mounted upon the end of a sliding and rotary spindle, the spindle and hook being moved longitudinally toward and from the wire to grasp and loop the same, and rotated to twist the loop held 30 upon the hook to form an eye, the twisting hook then discharging the loop or eye, after which the wire is fed a greater or less distance and is again grasped and twisted.

Figure 1 is a front elevation of a wire twisting machine embodying my invention with one flange of the reel removed; Fig. 2, a section to the left of the dotted line $x-x$ in Fig. 1; Fig. 3, an enlarged section to the left of the dotted line $x'-x'$, Fig. 1; Fig. 4, a section 40 below the dotted line x^2-x^2 , Fig. 2. Fig. 5 shows a piece of wire when looped by longitudinal movement of the twisting hook. Fig. 6 shows a piece of the completed bundle wire provided with the twisted eyes. Fig. 7 is a 45 vertical section of the reel taken on the line x^3-x^3 , Fig. 1, both flanges being shown. Fig. 8 is a side view of the ratchet plate detached; and Fig. 9 is a section below the dotted line x^2-x^2 , Fig. 2, with the twisting hook omitted.

50 Referring to the drawings, in the construction of machine which I prefer to employ, A

represents a table mounted upon suitable legs A', and said table has secured to it the base B of the twisting machine, said base having an upright B' provided with suitable bearings, as B², for the spindle B³ loosely connected at its upper end with a lever B⁴, pivoted at B⁵ on an ear of the upright, said lever having, as shown, at its front end suitable pins or projections 2, which enter from opposite sides a groove 5 in a block or collar a fastened to or forming a part of the upper end of the spindle. The spindle B³ is surrounded between the bearings B² by a sleeve B⁶, said sleeve being splined to said spindle by a spline 6, in order that the spindle may be raised and lowered longitudinally within said sleeve. The lower end of the sleeve B⁶ is provided with a beveled gear b, which is engaged by a larger beveled gear b', fast on a rotating shaft b², adapted to be rotated by power, manual or otherwise, but herein shown as manual, by means of a crank handle b⁸. The lower end of the spindle, as herein shown, is provided with a wire twisting device g, shown as a hook, connected with the spindle by a pivot g', said hook being normally retained in its position shown in Fig. 3, by a spring g². The spindle may be raised and lowered within the sleeve B⁶ by the lever B⁴, and the rod D extended preferably through a suitable treadle D' upon the floor. The wire w, which is to constitute the bundling wire, and which is to be twisted, will in practice be taken from a suitable reel or cop, not shown, and led 60 through suitable wire straightening devices C, of usual or desired construction, herein shown as consisting of a number of rolls or pulleys, between which the wire is drawn, the straightened wire, issuing from said devices, being led across the throat d, in a suitable groove in the latter, and under the bridge d', said throat having an opening d², below which in the bed-plate B is provided a pocket c. After the wire leaves the throat, it is passed 65 in the first instance about a measuring device E, shown as a disk provided with a peripheral groove e, in and about which the wire is passed one or more times, preferably once, after which it is led to the receiving spool or 70 reel, which is also the wire-feeding device, upon which it is wound until ready for use.

In the present instance, and preferably, the circumference of the base of the groove in the periphery of the measuring device, is equal to the distance between two adjacent eyes in the completed bundling wire, so that each rotation of the measuring device represents a feed of the wire sufficient to carry it from one eye to another during the formation of the eyes. The measuring device or disk is secured upon to rotate with a shaft e^2 , journaled in a suitable bearing e^3 , properly supported by the frame, the said shaft, as herein shown, at its rear end having secured to it a ratchet plate e^4 , shown separately in Fig. 8, with which co-operates a suitable detent e^5 , which latter by dropping into the notch e^6 in the ratchet plate retards the rotation of the measuring device and indicates to the operator whenever the measuring device has made one complete revolution. The bed plate B has mounted upon it a hold-down f , the same having a sliding movement, it being pushed forward to overlap the wire w during the twisting operation, and thereafter drawn back to permit the feed of the wire with the loop or eye formed in it, a slot f^x in the hold-down entered by a screw 8 permitting such movement. The hold-down is moved preferably by an elbow-lever f' , and a link f^2 attached at one end as at f^3 to the lever B^4 , and slotted at its opposite end to embrace a pin 7 on the elbow-lever, the hold-down being pushed forward over the wire immediately before the spindle rises. Spring g^x acts normally to lift the treadle and depress the spindle. When the spindle is in its depressed position, the hook which constitutes the twisting device, occupies a position in the pocket c and below the wire w as shown in Fig. 3, the inclined side wall c^x of said pocket holding the hook in its rear or abnormal position against the action of the spring g^2 .

The operation of the machine is as follows, viz:—The operator by depressing the treadle, lifts the spindle and hook, the latter, as soon as it leaves the inclined surface c^x , being moved to the left by the spring g^2 into position directly beneath the wire, which latter it engages as the spindle is lifted, and bends the wire into an inverted U-shaped loop (see Fig. 5) between the bridge d' and the hold-down f . The handle b^3 is now turned to rotate the spindle with its attached hook holding the loop thus formed, and thereby twists the loop upon itself and about the hook one or more times, to form an eye, as shown in Fig. 6. The treadle is then released to lower the spindle, the inclined under side g^x of the hook, as the latter is lowered, striking the bottom of the eye just made and being thereby forced to the right out of engagement with the eye, the latter being retained in its upright position and from following the hook as it retreats, by means of two inwardly projecting pins or projections 9 and 10, upon the inner faces respectively of the bridge and hold-down (see Figs. 4 and 5), further move-

ment of the spindle bringing its hook into contact with the inclined face c^x of the pocket c , thereby throwing the hook to the right sufficient to clear the eye when the wire is fed forward. The operator now rotates the reel which constitutes a wire-feeding device by means of a suitable handle applied to the squared end of its shaft to draw or feed the wire forward through the machine preparatory to the formation of a new eye, the wire being drawn forward until the detent e^5 which has been raised by the inclined rear edge e^7 of the notch e^6 drops into the notch again when the ratchet plate e^4 has made one revolution, indicating that the measuring device has made one complete revolution, and has therefore fed the wire the proper distance between two adjacent eyes, when the feed is stopped and another eye formed in the wire, as in the manner hereinbefore set forth.

It will be noticed that the axis of the measuring device E is not perpendicular to the direction of feed of the wire, but stands at an angle thereto, so that the wire having the eyes formed in it, as it passes about the groove in the periphery of the measuring device, will pass about the same spirally, so that an eye in the wire having passed about the device and rising upon the back side thereof, will stand at one side of and thereby clear the wire leading to the measuring device from the eye-forming mechanism, so that said eye will not interfere with the proper feeding of the wire.

I have herein shown and prefer to employ a peculiarly constructed reel which is the receiving and feeding device in order to facilitate the removal of the cop when the reel is full.

Referring to Figs. 1 and 7, the reel consists of a core F' provided with two end flanges F^2 , F^3 , one of which, as F^3 , is removable, and in Fig. 1 said flange is supposed to be removed. A split sleeve, preferably in the form of a thin steel plate m , surrounds the core F' of the reel, said sleeve having a V-shaped depression m' formed at one side and having its abutting ends m^2 turned inwardly at the opposite side of the core to thereby support the sleeve always at a distance from the core and retained thereupon solely by the friction at the points m' and m^2 . When the reel has been filled with the completed bundle wire, the movable flange F^3 (see Fig. 7) is taken off and the cop and sleeve m slipped from the core, this being easily done by reason of the slight friction between the points m' and m^2 of the sleeve and the core. A wire may then be passed under the cop through the depression m' , or through the opening left by the in-turned ends m^2 of the sleeve, and passed about the cop to tie the same firmly together, after which the sleeve itself may be easily withdrawn from the cop by springing it inwardly by the fingers or by means of some thin tool, and again placed upon the reel.

This invention is not limited to the particular construction or arrangement of parts

herein shown to illustrate this invention, for it is evident that the same may be varied in many particulars without departing from the spirit and scope of the invention.

5 I claim—

1. In a machine for the manufacture of continuous bundling wire, a wire straightening device, a wire feeding device, and a rotating measuring device to determine the length of the wire between loops, combined with means to form a loop and to thereafter twist a loop one or more times upon itself to form an eye, substantially as described. 65
2. In a machine for the manufacture of continuous bundling wire, wire straightening devices, independent holding devices to overlap the wire, wire feeding devices, a twister and means to move the latter transversely toward and from the wire to come under and draw up the wire in loop form, and means to impart a rotative movement to the twister relatively to the said wire holding devices, to thereby twist the loop into an eye, while the wire is overlapped by said devices at each side thereof substantially as described. 70
3. In a machine for the manufacture of continuous bundling wire, wire holding devices, a rotatable twister, and means to move the same transversely toward and from the wire to loop the same between the holding devices, the rotation of the twister thereafter acting to twist the loop so formed one or more times upon itself into an eye, substantially as described. 75
4. In a machine for the manufacture of continuous bundling wire, wire holding devices, a twister hook, means to move the same toward and from the wire to loop the latter between the holding devices, and also means to rotate said hook to twist the loop one or more times upon itself into an eye, substantially as described. 80
5. In a machine for the manufacture of continuous bundling wire, wire holding devices, a longitudinally movable and rotatable spindle, a twister hook connected to said spindle, and means to move the said spindle longitudinally to cause the hook to engage the under side of the wire and draw up a loop there- 85
- 50 in between the holding devices, rotation of the spindle and hook thereafter twisting the said loop upon itself into an eye, substantially as described. 90
6. In a machine for the manufacture of bundling wire, wire holding devices, a longitudinally movable and rotatable spindle, a twister hook connected to said spindle, means to move the said spindle longitudinally to cause the hook to engage and loop the wire, rotation of the spindle and hook twisting the said loop into an eye, and devices to retain the completed eye in position during withdrawal of the hook to prevent it following the latter, substantially as described. 95
7. In a machine for the manufacture of bundling wire, independent wire holding devices, one of which is movable to hold and release the wire alternately, a longitudinally movable and rotatable spindle, a twister hook connected to said spindle, and means to move the said spindle longitudinally to cause the hook to engage and loop the wire between the holding devices, rotation of the spindle and hook thereafter twisting the said loop upon itself into an eye, substantially as described. 100
8. In a machine for the manufacture of bundling wire, wire holding devices, a twister hook to engage and loop the wire, the under side of said hook being beveled, and means to rotate said hook to twist the wire to form an eye, the beveled under side of the hook acting against the bottom of and being thereby thrown out of engagement with said eye when the hook is moved toward the wire, substantially as described. 105
9. In a machine for the manufacture of bundling wire, wire holding devices, a longitudinally movable and rotatable spindle, a spring-controlled twister hook carried thereby, and the pocket *c* and its inclined wall *c'* to throw the hook away from the wire, substantially as described. 110
10. In a machine for the manufacture of bundling wire, wire holding devices, eye forming and twisting devices to form an eye between the holding devices, and a rotatable measuring device about which the wire is passed, and means to check rotation of the said measuring device after a predetermined rotary movement to thereby determine the length of feed of the wire and the distance between eyes in the wire, substantially as described. 115
11. In a bundling wire machine, the herein described reel, the same consisting of a core and a surrounding split sleeve, said sleeve having at one side of the core a V-shaped indentation, and having its facing edges turned inwardly at the opposite side to thereby support said sleeve out of contact with said core, substantially as described. 120
12. In a machine for the manufacture of bundling wire, the following instrumentalities, viz:—wire holding devices, eye forming and twisting devices, and a rotatable measuring device *E*, about which the wire is passed and set at an angle to cause the wire to be wound about the same spirally, substantially as and for the purpose specified. 125

In testimony whereof I have signed my name to this specification in the presence of two subscribing witnesses.
